(57) **CLAIM**

The ornamental design for an end cap for cable management system, as shown and described.

DESCRIPTION

FIG. 1 is a front perspective view of my design for an end cap for cable management system;

FIG. 2 is a front elevational view thereof;

FIG. 3 is a top plan view thereof; and,

FIG. 4 is a left side view thereof (the right side view is a mirror image of the left side view).

The broken lines shown on the drawings are included for the purpose of illustration and form no part of the claimed design.
